2 Claims. (Cl. 271—1)

ABSTRACT OF THE DISCLOSURE

Apparatus for use in combination with an automatic packaging machine which is adapted to lift a pre-selected part of a stack of lids in timed relation to means for sliding the bottommost lid from the stack of lids so that the weight of the lifted part of the stack of lids will not interfere with the sliding.

This invention relates to packaging apparatus and, more particularly, relates to cartoning apparatus comprising means for automatically dispensing carton lids.

Various commercial packaging machines are available which provide for automatic dispensing of cartons, filling the cartons with a desired product, dispensing lids in proper relation to the cartons, and closing the cartons. Such commercial machines, however, are designed for general use in dispensing and filling a wide variety of cartons and appropriate lids. Frequently, operating difficulties are encountered when these commercial machines are used for filling and sealing a particular carton and lid arrangement, and one such particular difficulty relates to dispensing of the lids.

One type of automatic dispensing device for the lids operates to remove the bottommost lid from a stack of lids by sliding the lid from beneath the stack. The weight of the stack of lids tends to impede such sliding and frequently the lid is distorted or bent during the dispensing operation. Such bending or distortion of the lid during dispensing not only results in rejection of the carton to which it is applied, but may also result in jamming and stopping the machines, causing considerable expense and delay from machine downtime.

Accordingly, it is the principal object of the present invention to provide improved means for dispensing lids in automatic packaging machinery. Another object is the provision of apparatus for use in combination with an automatic packaging machine whereby lids may be dispensed without bending or distorting such lids.

These and other objects of the invention are more particularly set forth in the following detailed description and drawings in which:

FIGURE 1 is a fragmentary top view of an embodiment of apparatus suitable for the practice of the present invention attached to the lid dispenser base of a commercial rotary filler and capper;

FIGURE 2 is a fragmentary side view, partially broken away and partially in cross-section, of the apparatus of FIGURE 1, the apparatus having a slide in a first position and showing, in phantom outline, the slide and cooperating components in a second position;

FIGURE 3 is a sectional view taken along line 3—3;

FIGURE 4 is a sectional view taken along line 4—4; and

FIGURE 5 is an overall pictorial view of the apparatus of the present invention in combination with automatic packaging means.

The apparatus of the present invention, as shown in the drawings, is especially adapted for lifting a pre-selected part of a stack of lids in an automatic packaging machine. The apparatus includes lifting means which are actuated in timed relation to means for sliding the

2

bottommost lid from a stack of lids so that the weight of the stack of lids will not interfere with the sliding. Although it is contemplated that the apparatus is suitable for use with other type lids, its principal intended use is with aluminium lids and particularly with aluminium lids which include an opening tab.

In general, with reference to FIGURES 1 and 2, the apparatus of the present invention comprises a slide 11 having a pair of spaced bushings 13 and 15, a lever 41 pivotally connected to the slide 11 which cooperates with a crankshaft 31 to move the slide 11 from a first position to a second position, and a pair of arm assemblies 51 and 53 which are journaled to the bushings 13 and 15, and which are spaced on opposite sides of a stack of lids 71.

The lifting effect on a portion of the stack of lids is achieved by moving the slide 11 from a first position, as shown specifically in FIGURE 2, to a second position, shown in phantom outline, thereby simultaneously moving 20 the arm assemblies 51 and 53 rotatably around bushings 13 and 15 and linearly in the direction of movement of the slide 11 so that jaw members 61 and 63 move generally inwardly and upwardly to grasp and lift a pre-selected part of the stack of lids.

In the specific embodiment illustrated, the slide 11 is of generally rectangular shape with the bushings 13 and 15 disposed in space relation at one end of the rectangle and an aperture 17 located at the opposite end of the slide.

As best seen in FIGURE 4, the entire slide is adapted 30 to be mounted in a track 23 which confines the lateral movement of the slide when it is moved from a first position to a second position. The track 23 is defined by slide backing plate 25 in combination with gibs 27 and 29 and gib plates 31 and 33.

As best seen in FIGURE 3 the slide backing plate is fastened, by welding or like means, at right angles to a base plate 22 to provide a slide track assembly which may be appropriately located with respect to the stack 40 of lids 71, a convenient method of location being to fasten the slide track assembly to the lid dispenser base 73.

The slide 11 is actuated from a first position to a second position by the lever 41 in combination with the crankshaft 31. The crankshaft 31 operates in timed relation with automatic dispensing, movement, and filling of cartons (as shown in FIGURE 5) and with automatic lid sliding means (not shown) for removal of lids from the stack 71. The crankshaft 31 is coupled with the lever 41 by connecting rod 42. The lever 41 is pivotally connected to the slide backing plate 25 with a shoulder bolt 43 to provide a fulcrum intermediate between opposite ends of the lever. The lever 41 is provided with a slot 45 at the end opposite the connecting rod which is engaged with the aperture 17 of slide 11 by a shoulder bolt 47. The slot 45 is sufficiently long to accommodate variations in distance from the fulcrum of the lever to the slide aperture caused by moving the slide in the track from a first position to a second position.

The arm assemblies 51 and 53, best seen in FIGURES 1 and 2, which are journaled to the bushings 13 and 15 of the slide 11 are restrained from gravitational rotation by adjustable stops 55 and 57, which may be hexhead bolts and lock nuts. As the slide 11 moves from a first position to a second position, as shown in FIGURE 2, the arm assemblies move from a horizontally disposed position to an inclined position. This serves to move the face of the jaw members 61 and 63 inward and upward to grasp and lift a pre-selected portion of the stack of lids 71. To avoid damaging the lids as they are grasped, the jaw members are faced with a suitable soft resilient mate-

rial 65, such as neoprene, Teflon or the like. As seen in FIGURES 1 and 2, the jaw members are preferably circularly concave in one plane to conform to the circular edge shape of the lids and preferably convex in a perpendicular plane to provide a suitable shape for initial contact with the edge of the lids, although other shapes are also considered suitable as will be readily apparent to one skilled in the art.

In operation, the slide 11 is actuated by the lever 41 in cooperation with the crankshaft 31 from a first position to a second position in timed relation so that the arm assemblies 51 and 53 are moved to a position such that the jaw members 61 and 63 have grasped and lifted a pre-selected portion of the stack of lids 71 before sliding means engage the bottommost lid of the stack to slide the lid from the stack. When the slide is moved from the second position to the first position, the stack is released momentarily by the jaw members to permit escape from the lifted part of the stack of at least one lid.

It is readily apparent that various modifications may be made to the apparatus of the present invention by one skilled in the art without departing from the scope of the invention which is defined in the appended claims.

What is claimed is:

1. In packaging apparatus which includes means for sliding a lid from the bottom of a stack of lids, the combination comprising lifting means adapted to engage and lift at least a portion of the stack of lids adjacent the bottom lid of the stack and means actuating said lifting means so as to relieve the weight of a portion of the stack

from the bottom lid while the lid is removed by the sliding means, said lifting means comprising a slide and at least two arms rotatably mounted to said slide, each of said arms having jaws attached thereto, said slide being adapted to move from a first position wherein said jaws are adjacent the stack to a second position wherein said jaws engage and lift the stack of lids adjacent the bottom lid of the stack by said actuating means.

2. The apparatus of claim 1 wherein said lifting means comprises a slide having two bushings mounted thereon, an arm rotatably attached to each of said bushings, each of said arms having jaws attached thereto, a slide track wherein said slide is engaged, and said actuating means comprises a lever and a connecting rod, said connecting rod being rotatably attached to the end of said lever and said connecting rod being actuated in timed reciprocating motion so as to move the end of said lever from a first position to a second position, said lever being pivotally mounted and attached to said slide so as to move said slide from a first position wherein said jaws are adjacent the stack of lids to a second position wherein said jaws engage and lift the stack of lids adjacent the bottom lid of the stack when actuated by said connecting rod.
